UNITED STATES PATENT OFFICE

HARRY B. RUDD, OF DOUGLASTON, NEW YORK

METHOD OF AND APPARATUS FOR UTILIZING PHASE-CHANGEABLE MATERIAL

Application filed June 24, 1929. Serial No. 373,134.

My invention relates to a method of sealing a container; my invention also relates to a container-sealing arrangement involving a member or plate held in container-closing 5 position by pressure exerted thereon from the interior of said container.

In accordance with one prominent form of my invention, the aforesaid pressure is developed by a gaseous medium resulting from 10 change in phase of one or more blocks or masses of solid or semi-solid ice-like material of carbon dioxide, for example, the latter being hereinafter generically termed "solid material" or "solid carbon dioxide," 15 as the case may be.

My invention relates to a container arranged to be sealed in a novel, simple and highly practical manner.

Further advantages, objects, and characteristics of my invention will become apparent from the following detailed description taken in connection with the accompanying drawing.

My invention resides in the method, arrangement, apparatus and features of construction of the character hereinafter described and claimed.

For an understanding of my method and for an illustration of one of the forms my 30 novel sealing arrangement may take, reference is to be had to the accompanying drawing, in which:

The figure is a vertical sectional view, partly in elevation, illustrating a container and 35 a sealing arrangement therefor together with a diagrammatic illustration of a conduit system traversed by material passing from said container.

As herein illustrated and described, my 40 invention has general reference to a system for utilizing liquid and/or gaseous material resulting from change in phase of solid material disposed in a casing or container. More particularly, my invention relates to an improved type of container or casing receiving the aforesaid solid material and embodying a novel arrangement for sealing the same. Still more particularly, my invention relates 45 to a container or casing receiving solid material and which is an improvement over the

container utilized for the same purpose and disclosed in my pending application Serial No. 341,712, filed February 21, 1929.

Referring to the drawing, C represents a casing or container of any suitable size, shape 55 or configuration, the wall structure thereof, ordinarily, being formed from iron or steel having sufficient thickness to resist deformation such as may be occasioned by high pressure existing interiorly of said casing or container. 60

In the example illustrated, container C comprises a bottom wall from which rises circular wall structure having, at the top thereof, a cap member 1 threaded or otherwise 65 suitably secured thereto, said cap member 1 comprising an opening or aperture 1a through which material may be passed to the interior of said container C, as more particularly hereinafter described. The cap member 1, 70 in the example shown, has secured thereto by a chain 2, or the like, a member or plate 3 ordinarily formed from relatively thick metallic material and which should be of such configuration and have such area that, when 75 placed in the proper position, it closes the aforesaid opening 1a of cap member 1. To increase the efficiency of the sealing action, member 3 may comprise a flange 3a of such configuration, when in the position illustrated, that it entirely encompasses the opening 1a of cap member 1. As hereinafter more fully described, flange 3a, in response to manipulation of member 3 by a chain 4, or equivalent, is adapted to be received by a 80 channel formed on the lower surface of cap member 1, said channel preferably containing a gasket 5 formed of rubber or the like. 85

Preferably but not necessarily the aforesaid opening 1a is circular, as is the channel 90 on the inner surface of member 1. Under such circumstances, the flange 3a is circular and the same may be true of the plate 3. Accordingly, when the construction is of the character just described, it is impossible to 95 pass the member 3 through the opening 1a and, therefore, the latter is disposed interiorly of the container side wall structure prior to the time that the cap member 1 is threaded thereto. With the latter in the 100

position illustrated, member 3 is suspended therefrom by the chain 2 or is maintained in container-sealing position as illustrated by pressure exerted thereon from interiorly of said container.

5 As illustrated, container C may be disposed within a suitable housing H having a detachable cover 7.

Communicating with the container C, immediately adjacent the bottom thereof and near the top thereof are the conduits 8 and 9 each of which is controlled by a valve 10. Opening into the container C, preferably immediately adjacent the top thereof, is a 15 relief valve 11 of any suitable construction.

With the housing cover 7 removed and with the container C empty, the member 3 hangs downwardly therein under the influence of gravity and is supported solely by 20 the chain 2. At this time, one or more blocks or masses I of the aforesaid solid or semi-solid carbon dioxide may be introduced into the container C through the opening 1a of cap member 1. Chain 4 may now be 25 grasped manually and the member 3 moved into substantially the position illustrated, the flange 3a thereof entering the channel of cap member 1.

30 The solid or semi-solid carbon dioxide blocks or masses I are in unstable equilibrium and immediately after being placed in the container C, there is an evolution of carbon dioxide gas. Accordingly, the member 3 may be manually or otherwise suitably retained in the position illustrated for a brief 35 period or until the gas pressure within the container C builds up or increases to an extent sufficient to positively retain said member 3 in the position illustrated. As the 40 gas pressure within the container C increases to greater and greater extent, the member 3 is more firmly held in such position and the flange 3a thereof in conjunction with the gasket 5 causes said container C to be positively sealed at the opening 1a.

45 After the sealing operation has been effected as described above, the blocks I continue to change to the gaseous phase and, with increasing pressure, the blocks change 50 to the liquid phase to thereby produce in said container C a body of liquid carbon dioxide maintained under great pressure.

55 Principally the liquid medium thus obtained may be passed through the conduit 8 to a device D for returning the liquid carbon dioxide to the solid or semi-solid phase as described and claimed in my aforesaid pending application Serial No. 341,712, filed February 21, 1929. The device D may be of any 60 character suitable for accomplishing this purpose and, in the example illustrated, corresponds generally with that disclosed in my pending application, Serial No. 320,060, filed November 17, 1928. When constructed 65 as disclosed in said last named application,

the device D comprises a hinged cap 12, in part, defining a chamber 13 wherein the aforesaid liquid carbon dioxide is expanded to form a mass of solid or semi-solid carbon dioxide, passage of said liquid medium to said chamber 13 being controlled by a suitable valve actuated by a member 14. After the last named mass of material has been produced or formed, a member 15 may be actuated to release the cap 12 whereupon the latter may be swung on its pivot to open the chamber 13.

70 If desired and also as described in my aforesaid pending application Serial No. 341,712, filed February 21, 1929, the conduit 9 may be traversed principally by carbon dioxide gas, the said conduit 9 leading to suitable carbonating apparatus, not shown, or, if desired, the gaseous material traversing the conduit 9 may be otherwise suitably 75 utilized.

80 As illustrated, duplicate containers C are disposed in the housing H in side-by-side relation, the conduits 8 and 9 being connected to both of said containers. A duplicate container arrangement per se is advantageous where the blocks or masses I are produced in a central plant, as they usually are. Accordingly, the container C may be alternately utilized one of them receiving, for example, a 85 supply of the blocks I on one day and the other of them receiving a supply of blocks at a later date as claimed in my aforesaid pending application Serial No. 341,712 filed February 21, 1929. Obviously, after continued 90 use of one of the containers C, the gas pressure therewithin drops to such an extent that the member 3 may readily be removed from its sealing position after a suitable venting 95 operation.

100 If desired, the containers C may be modified ordinary carbon dioxide drums disposed in inverted relation. The member 1 is substituted for the usual bottom drum wall and the usual upper conical section of the drum is cut away and replaced by a member such as herein shown as forming the container bottom wall.

105 Although my invention has been more or less specifically described in connection with carbon dioxide, it shall be understood that other materials may be utilized in lieu thereof.

110 In the appended claims where it is specified that a closure plate is adapted to contact with the lower surface of the container top wall, it shall be understood that this language is broad enough to cover an arrangement wherein the closure plate contacts with the lower top wall surface indirectly in the 115 sense that a gasket or the like may be interposed between said plate and said top wall.

120 While the invention has been described with respect to a certain particular preferred example which gives satisfactory results, it 125

will be understood by those skilled in the art after understanding the invention, that various changes and modifications may be made without departing from the spirit and scope of the invention and it is intended therefore in the appended claims to cover all such changes and modifications.

What is claimed as new and desired to be secured by Letters Patent is:

1. The method of sealing the filling opening of a container, which comprises introducing phase-changeable solid material into said container through said opening, and thereafter retaining a closure plate in sealed

15 relation with respect to said opening solely by the pressure exerted thereon by gas arising from change in phase of said solid material.

2. The method of sealing the filling opening of a container, which comprises introducing solid carbon dioxide into said container through said opening, and supporting a closure plate in sealed relation with respect to said opening until the evolution of carbon dioxide gas causes the pressure interiorly of said container to become slightly greater than that of the atmosphere, the gas pressure within said container serving solely thereafter to retain said closure plate in 30 said sealed relation.

3. The method of sealing the filling opening of a container, which comprises introducing solid carbon dioxide into said container through said opening, and by manual action 35 supporting a closure plate in sealed relation with respect to said opening until the evolution of carbon dioxide gas causes the pressure interiorly of said container to become slightly greater than that of the atmosphere, 40 said manual action being thereafter discontinued and the gas pressure within said container serving solely to retain said closure plate in said sealed relation.

4. In combination, a container having a 45 surface defining a filling opening, solid carbon dioxide being disposed in said container by passage through said filling opening, a closure plate interiorly of said container and adapted to contact with said surface to 50 seal said filling opening, said closure plate being retained in sealing relation by pressure of the gas evolved from said solid carbon dioxide.

5. In combination, a container having side 55 wall structure and a top wall, said top wall being apertured to define a filling opening, solid carbon dioxide being disposed in said container by passage through said filling opening, a closure plate interiorly of said 60 container and adapted to contact with the lower surface of said top wall to seal said filling opening, said closure plate being retained in sealing relation by pressure of the gas evolved from said solid carbon dioxide.

6. In combination, a container having a

surface defining a filling opening, solid carbon dioxide being disposed in said container by passage through said filling opening, a closure plate interiorly of said container and adapted to contact with said surface to seal 70 said filling opening, said closure plate being retained in sealing relation by pressure of the gas evolved from said solid carbon dioxide, and valve means for releasing pressure within the container to allow free downward movement of said closure plate from said surface whereby access may be had to said container through said filling opening.

7. In combination, a container having side 75 wall structure terminating at its upper end in a flanged top wall, said flange top wall being apertured to define a filling opening, solid carbon dioxide being disposed in said container by passage through said filling opening while said flanged top wall is in 80 position on said side wall structure, a closure plate interiorly of said container and adapted to seal said filling opening when moved into engagement with the lower surface of said flanged top wall, said closure 85 plate being retained in sealing relation by pressure of the gas evolved from said solid carbon dioxide.

In testimony whereof I have signed my name to this specification.
